ATTORNEY

UNITED STATES PATENT OFFICE.

GEORGE J. MARTIN, OF EAU CLAIRE, WISCONSIN.

TREE-SUPPORT.

1,287,069.

Specification of Letters Patent. Patented Dec. 10, 1918.

Application filed March 11, 1918. Serial No. 221,721.

To all whom it may concern:

Be it known that I, GEORGE J. MARTIN, a citizen of the United States, and resident of Eau Claire, in the county of Eau Claire and State of Wisconsin, have invented certain new and useful Improvements in Tree-Supports; and I do hereby declare that the following is a full, clear, and exact description thereof.

10 My invention relates to new and useful improvements in supports, and more particularly to holders for Christmas trees.

One of the objects of the invention is to provide a simply constructed and efficient holder of this character which may be inexpensively manufactured in view of the fact that the machine-work has been reduced to a minimum. In other words the device is constructed almost entirely of cast or pressed metal parts.

A further object of the invention is to provide means in connection with a water tight container for holding a tree or the like centrally therein.

25 A still further object is to provide a water tight container of improved design with readily detachable supporting legs.

With these and other objects, and the obvious advantages which may be derived therefrom in view, the invention resides in certain novel features of construction, combination and arrangement of parts which will be hereinafter more particularly described and claimed and shown in the drawing wherein:

Figure 1 represents a substantially central vertical sectional view of a tree holder constructed in accordance with the invention, and

40 Fig. 2 is a plan view of the device.

Referring more particularly to the drawing it will be noted that the invention consists essentially of a vertically elongated, preferably cylindrical, water tight container 1 and supporting means therefor. The top of the container is open and is provided with an outwardly extending radial flange 2 through which the wall of the container is formed a number of screw-threaded holes for the reception of the shanks of adjusting and clamping screws 3.

The bottom of the container 1 is rounded as at 4 and from its inner surface project a plurality of ribs 5. These ribs are pref-

erably diametrically opposed and have their inner edges inclined downwardly and inwardly as is shown most clearly in Fig. 1. Said ribs being relatively thin will bite into the lower end of the trunk of a tree or the like T when the same is forcibly projected into the container 1. The lower end of said tree is thus centered within the container and is held in vertical position by the adjusting and clamping screws 3 which are threaded into the container until the inner ends of their shanks engage said tree trunk.

Four diametrically opposed legs 6 are preferably used for holding the container in upright position, said legs being formed of strips of metal and are extended downwardly and outwardly from an annular collar 7, the inner ends of said legs being offset as at 8 and secured in any desired manner to said collar.

The outer lower ends of each pair of diametrically opposed legs 6 are connected by a base strip 9. As shown in Fig. 1 each corresponding pair of legs and their connecting base strip are preferably formed from a single strip of sheet metal. The outer end portions of the base strips are the surface engaging parts thereof, their intermediate portions being upwardly bowed and overlapped, the point of overlapping being centrally of the bottom of the container 1.

Said bottom is provided with a threaded stud 10 adapted to be disposed through alined openings in said overlapped portions of the base strips and to receive a retaining nut 11. Owing to the slight spring action of the sheet metal strips of which the legs 6 and base portions 9 are formed, the tightening of said nut 11 will tend to force the collar 7 upwardly and tightly engage the same with the shoulder formed by the radial flange 2. The collar therefore does not need to be secured to the container and if necessary said container may be revolved within said collar after the legs 6 have been secured to the floor or the like. This permits a Christmas tree to be readily positioned so that its most perfect side will be exposed.

Attention is also directed to the fact that the container 1 including the flange 2, the ribs 5 and the stud 10 may be cast, while the supporting means therefor is constructed of stamped sheet metal. In other words the

only necessary machine-work is the drilling and tapping of the holes for the screws 3 and the threading of the shank 10.

I claim:

- 5 1. A stand of the class described comprising a container open at its upper end, a peripheral flange formed on the container adjacent its upper end whereby to provide a shoulder, a collar surrounding said container and engaging the shoulder, a plurality of pairs of resilient laterally and outwardly extending legs having their inner ends secured to said collar, a resilient base strip connecting each corresponding pair of legs, said base strips being crossed and having aligned openings formed at their intersection, and means for connecting the bottom of the container with the intermediate portion of the base strips to force the collar against said shoulder.
- 10 15

2. A stand of the class described comprising a container open at its upper end, a collar surrounding said container adjacent its upper end, a plurality of pairs of laterally and outwardly extending legs having their inner ends secured to said collar, a base strip connecting each corresponding pair of legs, said base strips being crossed and having aligned openings formed at their intersection, and a stud extending from the bottom of the container to be disposed in the aligned openings of the crossed base strips.

In testimony that I claim the foregoing I have hereunto set my hand at Eau Claire, in the county of Eau Claire and State of Wisconsin.

GEORGE J. MARTIN.
